(57) CLAIM

The ornamental design for a buffet, as shown and described.

DESCRIPTION

FIG. 1 is a left front perspective view of a buffet showing my new design;

FIG. 2 is a side view, the opposite side being a mirror image thereof;

FIG. 3 is a front view; and,

FIG. 4 is a top view.

The broken lines showing the door hardware is for illustrative purposes only and forms no part of the claimed design.
